**CLIP FOR WRITING INSTRUMENTS
AND THE LIKE**

Frank T. Johann, 49 Hampton Drive,
Berkeley Heights, N.J.
Filed June 16, 1960, Ser. No. 36,658
5 Claims. (Cl. 120—42.03)

This invention relates to a clip for writing instruments and similar objects. In its preferred form, the invention relates to a pocket clip carried by a writing instrument in a recessed or retracted position when not in use and which may be projected into an operative position by means of a pushbutton.

Pocket clips are generally provided on pens, pencils, ballpoint instruments and the like whereby the instrument, when not in use, may be clipped to a pocket for carrying purposes. These clips conventionally have one end fixed to the carrying instrument, while the other end is free and spring-like. To fix such a clip to a pocket, it is necessary to force the cloth of the pocket between the free end of the clip and the carrying instrument. This usually requires the use of both hands, one hand to hold the pocket cloth and the other hand to force the instrument and clip into engagement with the cloth. In addition to being a somewhat unwieldy operation, continued use of such clips tend to actually tear the cloth or at least loosen the pocket seams. Furthermore, in the case of short writing instruments the conventional fixed clip can interfere with the hand grip on the instrument during writing.

In the present invention, I provide a clip which is movably mounted on the cap or barrel of the carrying instrument. When not in use, the clip is preferably maintained in a retracted position within a recess formed in said cap or barrel whereby it can appear as a normal portion of said cap or barrel. A pushbutton, carried by said cap or barrel, is connected so as to move the clip to a projecting position when depressed. In its projecting position, the main leg of the clip is preferably moved out sufficiently from the cap or barrel so as to provide a free space along the entire length of said leg. The clip may then be readily positioned over a shirt or coat pocket and the pushbutton is released. Upon release of the pushbutton, the clip moves inwardly towards its retracted position under the influence of a spring. However, it soon comes into contact with the cloth of the pocket and presses the cloth tightly against said barrel or cap to thereby hold the instrument to the pocket. To disengage from the pocket, the pushbutton can again be depressed to urge the clip to its projecting position, whereupon the instrument is then lifted upwardly and free of the pocket. Alternatively, the instrument is just pulled upwardly out of the pocket. In either case, once clear of the pocket and with pressure released from the pushbutton, the clip returns to its normal recessed position.

By the above type of mechanism, I provide a pocket clip which can be easily clipped to a pocket with one hand, which minimizes tearing of the pocket and which does not interfere with a normal writing hand grasp of the instrument. In addition, by having the clip, when recessed, preferably appear flush with the cap or barrel, the overall appearance of the instrument is improved.

The mechanism of my invention is preferably used with a ballpoint pen having a tip-actuated retractable point. In these tip-actuated pens, the ballpoint is retracted or protracted by pressing the writing end of the instrument against a rigid surface. Such pens make it possible to have a retractable point and at the same time have a pushbutton at the top of the pen to actuate the clip in a manner as previously described. However, my retractable clip can be used in other embodiments such as in fountain pen caps and other non-retractable pens. In addition to writing

2

instruments, the mechanism of the invention can be used with casings of small tools which have clips, e.g., electrical testing instruments.

The invention will be further understood by reference to the following description and accompanying drawings which include a preferred form of my invention.

In the drawings:

FIGURE 1 is a longitudinal sectional side view, illustrating a tip-actuated ballpoint pen with its point exposed and the clip in a recessed position in the barrel.

FIGURE 2 is a longitudinal sectional side view of the pen of FIGURE 1, with the point retracted and the clip projected preparatory to clipping the instrument in a pocket.

FIGURE 3 is a fragmentary front longitudinal view, partly in section, of the instrument of FIGURE 1.

FIGURE 4 is a cross-sectional view taken along the lines 4—4 of FIGURE 1.

FIGURE 5 is a cross-sectional view taken along the lines 5—5 of FIGURE 1.

FIGURE 6 is a longitudinal sectional view of a cap for a fountain pen, wherein the cap is provided with a retractable clip.

FIGURE 7 is a longitudinal sectional view showing a cap illustrating another embodiment of my invention.

FIGURE 8 is a cross-sectional view taken along the lines 8—8 of FIGURE 7.

Reference is now made to the drawings in detail, with particular reference to the embodiment of FIGURES 1 to 5. Here the casing of the writing instrument includes the upper barrel section 10 and lower barrel section 11, joined by threaded engagement with the tubular plug 12. The tubular section 10 is provided with a longitudinally extending recess 13 terminating at its upper end in a slot 14 which extends transversely through the barrel. A cap 15, frictionally engages the upper end of the barrel section 10 and is formed in its upper end with a slot or aperture 16. Fixed within the upper portion of the tubular section 10, is a cylindrical guide member 17 formed with a rectangular aperture 18 longitudinally extending through said member. Guide slots 19 are formed in the member 17 on either side of the opening 18, communicating therewith, and extending downwardly at an angle to the longitudinal axis of the instrument. The clip includes the main clip or leg portion 20, the transverse portion 21 and the upwardly extending pushbutton portion 22. The pushbutton portion 22 has two guide pins or ears 23 which transversely extend into and ride within the guide slots 19, while its upper end extends through the rectangular opening 16. A boss 24 is formed on the underside of the portion 21, said boss positions the upper end of the compression coil spring 25.

The lower portion of the barrel section 11, carries the longitudinally movable hood 26. The outer end 27 of the tubular hood is tapered inwardly so as to appear as a mere extension of the barrel. The inner end of said hood 26, is formed with an annular flange 28, which is engageable against the interior annular lip 29 formed in the barrel section 11. The bore extending through the hood 26 is reduced in cross-section at its lower end to form an annular lip 30. A point and cartridge unit indicated generally at 31, is mounted for longitudinal movement between a protracted position wherein its point 36 is extended through the outer end of said hood 26, and a retracted position wherein its point 36 is concealed within said hood. Said unit 31 includes: the reservoir tube 32 formed with the flange or flattened portion 33, the shoulder 34, the feed tube 35 and the writing ball 36 carried at the outer end of said tube 35. The upper end of the cartridge unit seats against the latch member 37, which in turn is formed with an annular groove 38 which

carries the locking ball 39. The top of the cylindrical latch element 37 is reduced in its cross section to define the upwardly projecting boss 40 which retains the lower end of the compression spring 25. An air vent 41, longitudinally extending through the member 37, allows the passage of air to the interior of the reservoir tube 32.

The latch mechanism includes the upper tubular latch member 42 and the lower tubular latch member 43, each of said members being fixed within the barrel in spaced relationship to each other. The members may be fixed to the barrel by frictional engagement, gluing, etc. The upper member 42 is formed with the downwardly extending teeth 44 and 45, each tooth having a tapered edge and a substantially vertical edge. The lower member 43 is formed with two upwardly extending teeth 46 and 47 which define a deep recess and a shallow recess. Each of said teeth 46 and 47 also have a tapered edge and a substantially vertical edge. All of said edges of teeth 44, 45, 46 and 47 are adapted for engagement with the locking ball 39.

FIGURE 1 shows the writing point 36 protracted and the pocket clip in its recessed position. By pressing the writing end of the instrument against a rigid surface, the point 36 and hood 26 are forced inwardly relative to the barrel section 11. As the point 36 moves inwardly, the cartridge unit 31 moves the latch member 37 upwardly against the pressure of spring 25 until its locking ball 39 engages the tapered side of the tooth 45. On further upward movement, the ball 39 moves along said tapered side until stopped by the vertical side of the tooth 44. Upon release of the lower end of the instrument from contact with the aforesaid rigid surface, the latch member 37, along with its locking ball 39, moves downwardly under the influence of the main spring 25. The ball 39 comes into contact with the tapered side of the lower tooth 46 along which it moves until stopped by the vertical side of the tooth 47. The ball 39 is now retained in the shallow recess between teeth 46 and 47 and is further upward within the barrel than before, thereby effectively shortening the spring 25. As the spring 25 is held shortened, the weaker compression coil spring 48, encircling the reservoir tube 32 and retained between flanges 33 and 28, is expanded. This results in maintaining the cartridge unit 31 further upward within the casing than before, while at the same time urging the hood 26 to its normal projecting position. The point 36 is now held concealed within the hood 26.

With the writing point 36 retracted, the instrument can be safely clipped within a pocket. By depressing the pushbutton 22, against the pressure of the spring 25, the guide pins 23 move down the guide slots 19. As a result, the clip 20 is moved out to an extended position as shown in FIGURE 2. With the clip extended as in FIGURE 2, it is apparent that it can be easily passed over a shirt or coat pocket so that when pressure is released on the pushbutton 22, the pocket will be firmly held between the leg 20 of the clip and the main body of the writing instrument. Thus, upon release of said pushbutton 22, the spring 25 urges the pushbutton 22 upwardly so that it tends to move along the guide slots 19 to its original position to thereby snugly engage the pocket material. The instrument can be readily disengaged from the pocket material by either again depressing the pushbutton 22 so as to move the clip back to its extended position thereby freeing the pocket material, or the instrument may be simply pulled off the pocket. In either case, once free of the pocket material, the spring 25 returns the clip to its original recessed position as shown in FIGURE 1.

When ready for writing use again, the point 36 may be protracted by again pressing the writing end of the instrument down against a rigid surface. The cartridge 31 will move upward as before, carrying the latch member 37 and locking ball 39 also upward. The locking ball 39 will thereby engage the tapered edge of the upper tooth 44 and be guided along said edge until stopped by

a vertical edge of the tooth 45. Then upon release of the instrument from contact with said rigid surface, the ball 39 and member 37 will move downward under action of the spring 25. However, the ball 39 will now strike the tapered edge of the tooth 47 and will be thereby guided to its original position in the deep recess as shown in FIGURE 1.

The embodiment of FIGURES 1 to 5 therefore illustrate a ballpoint pen having a fully retractable writing point and at the same time utilizing a pushbutton to actuate a retractable clip.

FIGURE 6 shows another embodiment of my invention, wherein a fountain pen cap is provided with my retractable clip. Here the main body of the cap 10' is internally formed with threads 50 at its lower end for engagement with a fountain pen 51. A guide cap 52 is frictionally engaged or otherwise fixed to the upper end of the tubular member 10'. The guide cap 52 is formed with a tapered top 53 and a rectangular slot or aperture 54. The clip includes the main clip portion 20', the transverse portion 21' and the pushbutton portion 22'. The pushbutton portion 22' extends upwardly through said aperture 54. A cylindrical plug 55, fixed within the tubular member 10', is formed with a boss 56. A compression coil spring 57 has one end surrounding said boss 56 and its other end surrounding a boss 24' formed on the underside of the clip portion 21'. Said spring 57 thereby always urges said pushbutton 22' upwardly and concurrently urges said clip portion 20' to its seated position within the recess 14'. A thumbpiece 58, is fixed to the upper end of the pushbutton 22' and straddles the rectangular slot 54. Preferably the upper edge of the member 58 is corrugated or otherwise roughened to form a better frictional grasp for a thumb or finger. In operation, the thumbpiece 58 is engaged with a thumb and urged downwardly along the slanting surface 53. This in turn urges the clip 20' to an extended position sufficient that it can be passed over a pocket. Once positioned over the pocket material, the member 58 is released. Then the upward force of the spring 57 will urge the clip portion 21' upwardly and inwardly so as to hold the pocket material firmly between the recess 14' and the inner side of the clip 20'. Release of the clip from the shirt material is accomplished either by again depressing the piece 58 or more simply by pulling the cap loose from the shirt in a more conventional manner.

FIGURE 7 represents still another embodiment of my invention. Here the invention is embodied in a cap adapted for frictional engagement with a ballpoint pen 59 having a fixed point 60. Here, I provide a main cap portion 10'' having the recess 14'' for reception of the main leg 20'' of a clip. A terminal cap 15'', frictionally engages the top end of the main cap portion 10'', and is formed with a recess 61 having a square cross-section, said recess communicating with a second recess 62 having a circular cross-section and extending through the top end of said cap 15''. Said recesses 61 and 62 define the shoulders 63 in said cap 15''. The pushbutton 64 extends through said recesses 61 and 62, and its lower portion has a square cross-section which prevents it from turning in said apertures. The lower end 65 of the pushbutton is tapered. Extending inwardly from the upper end of the clip leg 20'' is the transverse portion 66 having a tapered end 67 for engagement with the prior noted surface 65. A small flat spring 68 has its upper end formed into a hook 69 embedded or fixed within the cap 15''. The outer or lower end of said spring is bifurcated and passes over the portion 66 bearing against the flange 70 formed on the transverse portion 66. In operation, depression of the pushbutton into the cap urges the clip outward to a projecting position, against the pressure of the spring 68, due to the wedging action of the tapered end 65 of the pushbutton against the tapered end 67 of the clip. The clip may then be positioned over a pocket. Upon release of the pushbutton, the clip is

urged towards its retracted position within the recess 14" by action of the spring 68. This in effect will snugly engage the pocket material between the clip leg 20" and the casing. When the clip is released from engagement with the pocket, the tapered end 67 of the clip, because of the spring 68, will exert a wedging force against the pushbutton to thereby return said pushbutton to its original position as the clip is returned to its recessed or retracted position of FIGURE 7.

Other variations can be made of the present invention without departing from its broad scope. While the drawings show the outer surface of the clip flush with the casing when recessed, this is not essential. Thus, the mechanism does not require a recess at all, it only being essential that the clip be in an engaging position against the side of the casing when in a retracted position. Conversely, if a recess is provided, it is not essential that the clip leg 20 be projected completely out of the recess 13 by the pushbutton as the device is operable if the clip is projected sufficiently that it can then be engaged with a pocket, although this is less preferred. The invention may also be applied to mechanical pencils or similar objects.

In addition to the above variations, the mechanism of the invention can be actuated in ways other than previously described. For example, with regard to the embodiment of FIGURES 1 to 5, the pushbutton 22 in addition to being longitudinally moved downwardly into the casing, can also be pivoted about its pins 23 to increase the extent of outward movement of the clip leg 20, or if desired the clip may be solely actuated by a pivoting action.

I claim:

1. A writing instrument having a tip-actuated retractable writing point and a pushbutton actuated retractable clip comprising in combination, a tubular barrel having upper and lower ends, a longitudinally movable hood projecting through the lower end of said barrel, a cartridge unit including a ballpoint, said unit being longitudinally movable within said barrel between a point protracted position wherein said ballpoint extends through said hood and a point retracted position wherein said ballpoint is concealed within said hood, said barrel proximate said upper end being formed with a longitudinally extending recess, a pocket clip unit carried by said barrel including a downwardly extending clip portion, a transversely extending intermediate portion integral with said clip portion, and an upwardly extending pushbutton portion integral with said intermediate portion, guide means carried within said barrel engageable with said pocket clip unit, a helical coil compression spring disposed between said clip unit and said cartridge unit, said spring urging said pushbutton portion to an extended position projecting through said upper end of said barrel while urging said clip portion to a retracted position wherein said clip portion is within said recess whereby said clip portion is substantially flush with said barrel, said spring also urging said cartridge unit towards said point protracted position, and a retraction-protraction mechanism operable to obtain said cartridge unit in a point retracted position against the pressure of said spring upon pressing said hood and ballpoint into contact with a rigid surface and then releasing from said contact, said retraction-protraction mechanism being operable to allow said cartridge unit to be urged to its point protracted position by said spring upon a subsequent pressing of said hood and ballpoint into contact with a rigid surface and then releasing from said contact, said pushbutton portion being longitudinally movable against the urging of said spring into sliding contact with said guide means upon the application of downward force to said pushbutton portion wherein said clip portion is urged to a protracted position wherein said clip portion is projected from said recess, said pushbutton portion being moved to said extended position

and said clip portion being moved to said retracted position by said spring upon the release of said downward force.

2. In a ballpoint writing instrument having a longitudinal axis, a casing having upper and lower ends, said casing being formed with a recess; a ballpoint cartridge unit carried by said casing including a writing point; guide means carried by said casing defining a guide surface extending at an acute angle to said longitudinal axis of said instrument; an integral clip unit slidably engageable with said guide means including a transversely extending intermediate portion, a downwardly extending clip portion and an upwardly extending pushbutton portion projecting through the upper end of said casing, said pushbutton portion being longitudinally movable relative to said casing between an extended position and a depressed position; and a coil spring disposed between said cartridge unit and said clip unit whereby: (a) said cartridge unit is urged to a point projecting position, (b) said clip portion is urged to a retracted position within said recess whereby said clip portion is substantially flush with said casing, and (c) said pushbutton portion is urged to said extended position; said pushbutton portion being longitudinally movable against the urging of said spring into sliding contact with said guide means upon the application of downward force to said pushbutton portion whereby said clip portion is urged to a protracted position wherein said clip portion is projected from said recess, said pushbutton portion being moved to said extended position and said clip portion being moved to said retracted position by said spring upon the release of said downward force.

3. A writing instrument having a tip-actuated retractable writing point and a pushbutton actuated retractable clip comprising in combination, a barrel having upper and lower ends, a longitudinally movable hood projecting from the lower end of said barrel, a cartridge unit including a ballpoint, said unit being longitudinally movable within said barrel, said hood and said cartridge unit being shiftable relative to one another between a point protracted position wherein said ballpoint extends through said hood and a point retracted position wherein said ballpoint is concealed within said hood, a pocket clip unit carried by said barrel including a downwardly extending clip portion having a lower end, a transversely extending intermediate portion integral with said clip portion, and an upwardly extending pushbutton portion integral with said intermediate portion, supporting means carried within said barrel pivotally supporting said pocket clip unit, a helical coil compression spring disposed between said clip unit and said cartridge unit, said spring urging said pushbutton portion to an extended position projecting upwardly through said upper end of said barrel while urging said clip portion to a retracted position wherein said lower end of said downwardly extending clip portion seats against the side of said barrel, said spring also urging said cartridge unit towards said point protracted position, and a retraction-protraction mechanism operable to obtain said cartridge unit in said point retracted position upon pressing said hood and ballpoint into contact with a rigid surface to urge said hood and ballpoint inwardly relative to said barrel against the urging of said spring and then releasing from said contact, said retraction-protraction mechanism being operable to obtain said cartridge unit in said point protracted position upon a subsequent pressing of said hood and ballpoint into contact with a rigid surface to thereby urge said hood and ballpoint inwardly relative to said barrel and against the urging of said spring and then releasing from said contact, said pushbutton portion being depressed downwardly against the urging of said spring and pivoting about said supporting means upon the application of downward force to said pushbutton portion whereby said clip portion is urged to a protracted position wherein said lower end of said clip portion is held away from contact with said side of said barrel, said pushbutton portion being moved to said extended position

tion and said clip portion being moved to said retracted position by said spring upon the release of said downward force.

4. A writing instrument having a tip-actuated retractable writing point and a pushbutton actuated retractable clip comprising in combination, a tubular barrel having upper and lower ends, a longitudinally movable hood projecting from the lower end of said barrel, a cartridge unit including a ballpoint, said unit being longitudinally movable within said barrel, said hood and said cartridge unit being shiftable relative one another between a point protracted position wherein said ballpoint extends through said hood and a point retracted position wherein said ballpoint is concealed within said hood, a pocket clip unit carried by said barrel including a downwardly extending clip portion having a lower end, a transversely extending intermediate portion connected with said clip portion, and an upwardly extending pushbutton portion connected with said intermediate portion, beveled means carried within said barrel and engageable with said pushbutton portion whereby longitudinal movement of said pushbutton portion is translated into a transverse movement of said clip portion, a helical coil compression spring disposed between said clip unit and said cartridge unit, said spring urging said pushbutton portion to an extended position projecting upwardly through said upper end of said barrel while urging said clip portion to a retracted position wherein said lower end of said downwardly extending clip portion seats against the side of said barrel, said spring also urging said cartridge unit towards said point protracted position, and a retraction-protraction mechanism operable to obtain said cartridge unit in said point retracted position upon pressing said hood and ballpoint into contact with a rigid surface to urge said hood and ballpoint inwardly relative to said barrel against the urging of said spring and then releasing from said contact, said retraction-protraction mechanism being operable to obtain said cartridge unit in said point protracted position upon a subsequent pressing of said hood and ballpoint into contact with a rigid surface to thereby urge said hood and ballpoint inwardly relative to said barrel against the urging of said spring and then releasing from said contact, said pushbutton portion being longitudinally movable downwardly against the urging of said spring upon the application of downward force to said pushbutton portion whereby said beveled means moves said clip portion transversely to a protracted position wherein said lower end of said clip portion is held away from contact with said side of said barrel, said pushbutton portion being moved to said extended position and said clip portion being moved to said retracted position by said spring upon the release of said downward force.

5. A writing instrument having a tip-actuated retractable writing point and a pushbutton actuated retractable clip comprising in combination, a tubular barrel having

upper and lower ends, a longitudinally movable hood projecting from the lower end of said barrel, a cartridge unit including a ballpoint, said unit being longitudinally movable within said barrel, said hood and said cartridge unit being shiftable relative one another between a point protracted position wherein said ballpoint extends through said hood and a point retracted position wherein said ballpoint is concealed within said hood, a pocket clip unit carried by said barrel including a downwardly extending clip portion having a lower end, a transversely extending intermediate portion integral with said clip portion, and an upwardly extending pushbutton portion integral with said intermediate portion, beveled guide means carried by said barrel, said pushbutton portion being slidingly engageable with said beveled guide means, a helical coil compression spring disposed between said clip unit and said cartridge unit, said spring urging said pushbutton portion to an extended position projecting through said upper end of said barrel while urging said clip portion to a retracted position wherein said lower end of said clip portion seats against the side of said barrel, said spring also urging said cartridge unit towards said point protracted position, and a retraction-protraction mechanism operable to obtain said cartridge unit in said point retracted position upon pressing said hood and ballpoint into contact with a rigid surface to urge said hood and said ballpoint inwardly relative to said barrel against the urging of said spring and then releasing from said contact, said retraction-protraction mechanism being operable to obtain said cartridge unit in said point protracted position upon a subsequent pressing of said hood and ballpoint into contact with a rigid surface to thereby urge said hood and ballpoint inwardly relative to said barrel against the urging of said spring and then releasing from said contact, said pushbutton portion being movable downwardly against the urging of said spring in sliding engagement with said beveled guide means upon the application of downwardly directed force to said pushbutton portion whereby said clip unit is transversely shifted and said lower end of said clip portion is moved away from contact with said side of said barrel, said pushbutton portion being moved to said extended position and said clip portion being moved to said retracted position by said spring upon the release of said downwardly directed force.
